UNITED STATES PATENT OFFICE.

D FELLOWS COLLICUTT, OF COLUMBIA, SOUTH CAROLINA.

SCYTHE-SNATHE.

1,353,631.

Specification of Letters Patent. Patented Sept. 21, 1920.

Application filed March 3, 1917, Serial No. 152,371. Renewed August 4, 1920. Serial No. 401,282.

To all whom it may concern:

Be it known that I, D FELLOWS COLLICUTT, of Columbia, in the county of Richland and State of South Carolina, have invented certain new and useful Improvements in Scythe-Snathes; and I do hereby declare the following to be a full, clear, and exact description of the invention, such as will enable others skilled in the art to which it appertains to make and use the same.

The object of my invention is to so construct a scythe-snath as to enable the mowing of a wide swath without undue exertion on the part of the manipulator.

In the accompanying drawings, Figure 1 shows an elevation of the scythe, Fig. 2 an end view and Fig. 3 the position in use.

Referring to the drawings, 1 designates the snath which is formed with an upright portion 2 to the lower end of which the scythe-blade 3 is secured by any preferred means. As shown the tang 3^a of the blade carries a plate 6 having a cylindrical extremity 7. A sleeve 8 with binding screws 25 receives this extremity and that of the snath and permits of adjustment of the snath relative to the blade.

4 designates the gripping portion of the snath, forming a continuation of the upright 2 and occupying a position approximately at right angles thereto, and extending in the direction of the blade, the extreme end of the gripping portion being deflected upwardly to a slight degree. To the gripping or handle portion I secure nibs or handles 5 in the usual manner. The angular disposition of the handle portion relatively to the upright portion 2 is designed to bring

the blade and the handle portion substantially in parallelism and opposite each other, 40 that is, extending in the same direction from the portion 2, thus more effectively balancing the weight of the scythe in the hands of the operator. I have found that this permits an easier manipulation of the scythe and 45 requires a minimum of energy. The gripping portion 4 terminates within the length of the blade to better distribute the force.

It will be apparent that the scythe-snath may be adjusted to any required height and 50 that by means of the peculiar formation thereof the scythe will hang in such way that in mowing it will draw at right angles with the left-hand end nib, insuring a level draw on the sod. A snath so constructed will 55 have a wide circular sweep.

I claim as my invention:

In a scythe, a blade having a tang, a plate carried by said tang and formed with a cylindrical extension, a snath having a 60 straight portion, 2, a sleeve having binding bolts to receive the lower extremity of said portion 2 and the cylindrical extremity of said plate, and a handle portion, 4, on said snath extending at substantially right angles from said portion 2 in the same direction as the blade and substantially parallel with the blade.

In testimony whereof, I have signed this specification in the presence of two subscribing witnesses.

D. FELLOWS COLLICUTT.
